UNITED STATES PATENT OFFICE.

JOHN L. DINSMOOR, OF NEW YORK, N. Y.

SEAL.

Application filed October 28, 1921. Serial No. 511,138.

To all whom it may concern:

Be it known that I, JOHN L. DINSMOOR, a citizen of the United States, residing at the city of New York, borough of Manhattan, 5 county and State of New York, have invented a certain new and useful Seal, of which the following is a specification.

This invention is a device or instrumentality adapted for easy and expeditious application to an object of one character or another for affording protection thereto.

More particularly, the invention affords means for the permanent attachment to the seal member of a shackle, usually composed 15 of flexible material, such as a wire, cord, etc., said shackle being composed of material separate from the seal member and so united thereto or associated therewith that said shackle cannot by any possibility become detached accidentally or removed wilfully and fraudulently without leaving irrefutable evidence to the effect that the seal has been tampered with, disrupted or destroyed.

The invention in a broad aspect is susceptible of embodiment in different constructional forms, but fundamentally considered said invention is a member composed of flexible material, usually metal, bendable in definite directions for encasing, usually in a 25 partial manner, a shackle composed ordinarily of material differing in character from the seal member, together with a plurality of headed tubular studs integral with the seal member, said studs being of a compressible nature and operating when upset 30 for locking the seal parts and the shackle so securely and efficiently that the seal cannot be opened and reclosed for the removal of the shackle without occasioning such disruption of the seal as to wholly preclude reuse of the instrumentality as a means for sealing the shackle.

Other functions and advantages of the invention will appear from the following description taken in connection with the drawings, in which—

Figure 1 is a plan view of one form of the seal in an open condition and with a shackle assembled with reference thereto.

Figure 2 is a view in edge elevation of the parts shown in Figure 1, folded with the stud at one end between the other two studs.

Figure 3 is a view similar to that of Figure 2, showing one end stud folded under the middle stud.

The seal illustrated in Figure 1 comprises

the part or member L provided with three studs M N O and score or fold lines *m o* together with suitable designation or identification means. The stud N is provided with a slot or recess *n* for the reception of a looped portion of a shackle P, the latter preferably extending in a sidewise direction from the seal. The stud N is smaller in dimensions than studs M O, and said stud N projects in one direction from the seal body, whereas the other two studs M O extend in an opposite direction from said seal body.

The shackle is looped and positioned in an outward direction to the length of the seal, a small loop of the shackle being received into the slot or recess of the stud N. The seal is doubled on the line *m* for the stud O to fit over stud N, Figure 2 and then the longer part of the seal is doubled on the line *o* for the stud M to fit over the studs O N, after which pressure is applied for upsetting the studs and to effect the mutual interlocking engagement of the parts composing the seal. This mode of assembly brings the shackle within two opposite end loops of the seal, thus housing said shackle effectively against unwarranted tampering.

In some cases it is desirable to form stud O smaller than stud N and to fold stud O under stud N as shown in Figure 3.

The use of three studs in the scored seal enables the parts to be folded so as to accurately register the studs and to secure a quantity of metal which when the studs are upset afford added strength to the seal and increases materially the security afforded thereby. When the seal is closed, the tubular studs are quickly upset, and they are the only seal parts distorted by the compressive pressure.

Having thus fully described the invention, what I claim as new and desire to secure by Letters Patent is:—

1. A seal embodying a bendable member provided with shackle retaining means foldable to encase a shackle, and a plurality of locking means unitary with the bendable member, said locking means being compressible together with the shackle retaining means for locking the bendable part and the shackle retaining means into multiple folded relation.

2. A seal embodying a shackle the ends of which are united, a bendable member separate from the shackle and provided with

a shackle retaining tubular slotted stud, and means for locking said bendable member in folded relation to the united ends of said shackle, said locking means including a plurality of telescopic members crushable into locking engagement with each other and with said shackle retaining stud.

3. A seal of the class described embodying a foldable strip and three interlocking tubular studs one of which is provided with a shackle receiving recess.

4. A crushable seal of the class described embodying a foldable strip having shackle engaging means and three tubular studs one of which is provided with a recess and one of said studs being of slightly decreased di-

ameter relatively to the recessed stud and another of said studs being of slightly increased diameter relatively to said recessed stud whereby upon the assemblage of said studs into telescopic relation the three studs have frictional contact with one another respectively.

5. A seal of the class described embodying a foldable strip and three tubular studs adapted for assemblage into telescopic relation, the middle one of said studs being provided with a cord receiving recess.

In testimony whereof I have hereto signed my name this 22nd day of October, 1921.

JOHN L. DINSMOOR.
